US00D452823B1

(12) **United States Design Patent** (10) Patent No.: **US D452,823 S**
 Bezek et al. (45) Date of Patent: ** *Jan. 8, 2002

(54) **SNACK PACKAGING**

(75) Inventors: **Edward Anthony Bezek**, Frisco; **David Charlton McFadden, III**, Dallas, both of TX (US)

(73) Assignee: **Recot, Inc.**, Pleasanton, CA (US)

(*) Notice: This patent is subject to a terminal disclaimer.

(**) Term: **14 Years**

(21) Appl. No.: **29/143,612**

(22) Filed: **Jun. 14, 2001**

(51) LOC (7) Cl. **09-03**

(52) U.S. Cl. **D9/502**; D9/503; D9/518; D9/337

(58) Field of Search D7/12.1-12.2, D7/510-512; D9/307, 500, 502-505, 511, 513, 516, 518, 529-530, 539-542, 549, 558, 569, 574; 215/6, 381-384, 396, 398; 220/906; 423/43, 115, 120, 264, 583-584

(57) **CLAIM**

The ornamental design for a snack packaging, as shown and described.

DESCRIPTION

FIG. 1 is a top perspective view of the snack packaging of the present invention;

FIG. 2 is a side view of the snack packaging of the present invention;

FIG. 3 is a top view of the snack packaging of the present invention;

FIG. 4 is bottom view of the snack packaging of the present invention;

FIG. 5 is a bottom perspective view of the snack packaging of the present invention; and,

FIG. 6 is a perspective view of the snack packaging of the present invention, shown in exploded condition and showing the flexible pouch.
